MECHANICAL OR AUTOMATIC PENCILS

Joaquin Garcia Rey and Rubens Jesus Garcia,
Buenos Aires, Argentina

Application January 16, 1952, Serial No. 266,722

2 Claims. (Cl. 120—18)

The invention relates to improvements in mechanical pencils which are also known under the name of automatic pencils. The purpose of the innovation is that of offering to the user of the pencil an improved implement during use.

At present in all known types of mechanical or automatic pencils both hands are needed whenever it is wished to move the graphite rod or lead. A few of them are provided with a rotatory device which, when turned in one sense or another, produces the displacement of said graphite rod or lead. Others are provided at the opposed upper end with a press-button which also enables the advance of said rod or lead.

By means of the device which forms the subject-matter of this invention, the user will not need to interrupt his writing because, as soon as he notes that the point of the pencil is being worn down, it will be sufficient to turn with the thumb of the hand which is holding the pencil a knurled ring, whereby the point of the pencil may be advanced in the required length.

So as to explain clearly the nature of the invention and the manner in which it can be carried into practice, an example thereof will be described with reference to the accompanying drawings.

Figure 1 is a longitudinal, partly sectional view of increased size which corresponds to an improved pencil.

Figure 2 is a side elevational view of one of the elements contained in said improved pencil.

Figure 3 is a side elevational view of the improved pencil, but in natural size.

The new improved pencil consists of a cylindrical body 1 of any adequate material, such as metal or a plastic substance.

At one of the ends of said cylindrical body 1 an ample cylindrical cavity 2 will be provided. A cylindrical tubular element 4, force-fitted in a recess in the central part of bottom 3, terminates in cone 5 which constitutes the extremity of the pencil. Bore 6 of tubular element 4 is entirely cylindrical. Body 1, tubular element 4 and cone 5 form a rigid unity.

The body of tubular element 4 is of a smaller diameter than cavity 2 of body 1, whereby an annular space is provided therebetween into which nipple 7 will be put. Said nipple 7 is provided with an inner screw-thread 8. Upon part of the outer surface of nipple 7 a flange 9 is provided. Said flange 9 has a slightly greater diameter than body 1. The circular surface 10 of flange 9 is knurled so as to produce a roughness which will offer a better grip to the thumb when rotation is intended.

Tubular element 4 has upon the body thereof a longitudinal perforation 11. During mounting of the device two winged elements will be put into bore 6 of tubular element 4. One of them, viz. winged element 12, is tubular and in the interior thereof a part of the graphite rod 13 will be seated. Wing 14 which is solidary with element 12 passes through perforation 11 and will enter into screw thread 8 of nipple 7.

Another winged element 15 which conforms in width

to the perforation of tubular element 12 will be inserted therein. The winged end of element 15 will pass through the lateral perforation or slot of tubular element 12 and also through perforation 11 of tubular element 4 so as to enter finally also into screw thread 8 of nipple 7.

Winged element 15 will form the expelling means of lead 13.

When nipple 7 is turned with the thumb of the hand which holds the pencil, by means of knurled ring 10 of flange 9, element 12 which carries graphite rod or supply mine 13 will be displaced.

If turning of nipple 7 is continued, winged element 15 will progress along screw thread 8 and along the slot in tube 12 and will therefore push graphite rod 13 expelling it definitively from the device. When nipple 7 is turned in an opposite sense, a new graphite rod may be introduced in the device.

We claim:

1. In a mechanical pencil, a cylindrical body having a central cavity therein, an elongated fixed tubular guide casing having one end secured in said cavity and its other end enlarged and tapered and extending outwardly of the body, said guide casing having an elongated slot, a tubular member slidably mounted in said fixed tubular guide casing, an internally screw-threaded nipple member surrounding said fixed guide casing and being seated in the cavity of said cylindrical body, said slidable tubular member having an integral laterally screw-threaded extension extending through the slot in said guide casing and coacting with the threads on said nipple for sliding said tubular member, a rod of lead carried by said slidable tubular member, and a screw-threaded device slidably mounted in said tubular member in line with said rod of lead and adapted to coact with the threads on said nipple for expelling said lead from the slidable tubular member, said fixed tubular casing constituting a connection between its enlarged end and the cylindrical body, a guide and a housing for said tubular member, rod and expelling device.
2. In a mechanical pencil, a cylindrical body having a central cavity therein, an elongated fixed tubular guide casing having one end secured in said cavity and its other end enlarged and tapered and extending outwardly of the body, said enlarged end having a cavity, said tubular guide casing having an elongated slot, a tubular member slidably mounted in said fixed tubular casing, said tubular member having an elongated slot therein, an internally screw-threaded nipple member surrounding said fixed guide casing and being seated in the cavity of said cylindrical body and extending into the cavity in said enlarged end, said slidable tubular member having an integral laterally screw-threaded extension extending through the slot in said guide casing, and coacting with the threads on said nipple for sliding said tubular member, a rod of lead carried by said slidable tubular member, and an elongated device slidable in said tubular member in line with the rod of lead, said device having an integral laterally screw-threaded extension extending through the slots in said guide casing and in said tubular member and adapted to coact with the threads on said nipple for expelling said lead from the slidable tubular member, said fixed tubular casing constituting a connection between its enlarged end and the cylindrical body, a guide and a housing for said tubular member, rod and expelling device.
